UNITED STATES PATENT OFFICE.

HENRY J. SCHMICK, OF LOCK HAVEN, PENNSYLVANIA.

HOISTING MECHANISM.

1,245,623.

Specification of Letters Patent. Patented Nov. 6, 1917.

Application filed August 14, 1916. Serial No. 114,807.

To all whom it may concern:

Be it known that I, HENRY J. SCHMICK, a citizen of the United States, residing at Lock Haven, in the county of Clinton and State of Pennsylvania, have invented certain new and useful Improvements in Hoisting Mechanisms; and I do hereby declare the following to be a full, clear, and exact description of the invention, such as will enable others skilled in the art to which it appertains to make and use the same.

The invention relates to improvements in hoisting mechanisms.

The primary object of the invention is to provide a comparatively inexpensive and simplified device of the type mentioned, and one in which higher efficiency is to be obtained than is possible with the now known types of such devices.

Another object of the invention is to provide a device of this character, and one of a construction extremely light in weight for a given load to be lifted as compared with the various types of such devices now in use.

A further object of the invention is to provide a hoisting mechanism, wherein extreme economy in time in the hoisting operation obtains with a minimum amount of power applied for the accomplishing of such purpose.

A still further object of the invention is to provide a hoisting mechanism embodying all of the foregoing advantages, and one in which the load is readily sustained at any point within the range of the lifting movement without resorting to the use of additional or extraneous mechanisms, such as pawls or the like, as has heretofore been necessary in the known types of such devices.

With the foregoing, and other objects in view, the invention resides in the certain new and useful construction and arrangement of parts as will be hereinafter more fully described, set forth in the appended claim, and illustrated in the accompanying drawings, in which,

Figure 1 is a side elevation of the preferred embodiment of the same,

Fig. 2 is a vertical transverse section,

Fig. 3 is a vertical transverse section on the line 3—3 of Fig. 1,

Fig. 4 is a plan view of the cam gear, and,

Fig. 5 is an end view with the cam and the coverplate removed.

55

Fig. 6 is a plan view of the guide member for the operating chain.

Referring to the drawings, in which similar characters of reference designate corresponding parts in the several views thereof, the numeral 10 indicates the major portion of a housing having a removable side wall 11, and an angular offset portion 12, the latter being provided with a removable cover plate 13, the removable parts 11 and 13 being suitably secured in position on the integral portions 10 and 12, respectively, by means of screws 14. The housing 10 is formed with an upwardly projecting portion 15 in which is suitably secured a supporting hook 16, by means of which the device is suspended in any desired operative position.

The integral side wall 17 and the removable side wall 11 are each formed to provide 75 concentrically disposed bearings 18 and 19, respectively, in which are supported the oppositely disposed reduced portions 20 and 21, of a hub 22, the latter being integrally formed with a gear element 23, and having 80 its circular face, extending from one side of the gear element 23, formed with a plurality of communicating recesses 24. These recesses 24 are each shaped to receive alternate 85 links of a lifting chain 26, which is adapted to be trained over the hub 22, while the slots 25, connecting the recesses 24, are shaped to receive the alternate links connecting the first mentioned links of the chain. The lower portion of the major portion of the housing 10 is open, as at 27 to admit of the depending therefrom of the opposite legs of the chain 26, after the latter has been positioned on the hub 22, and is further provided with an integrally formed 90 partition wall 28 which snugly surrounds an intermediate portion of the hub 22 to provide an inclosed chamber for the gear 23, when the side wall 11 is properly secured in position.

95

100

To prevent accidental displacement of the lifting chain 26 in its travel over the hub 22, there is provided a guide member 29, positioned within the casing 10 and secured thereto at the point of greatest strain tending to lift a link from its corresponding recess, and the same is formed with a curved wall 30 having flanges 31 disposed at opposite sides and extending to either side of the path of travel of the chain. A second guide member 32 is supported transversely of the opening 27, by means of a screw 33, and projects upward in parallel relation to the opposite legs of the lifting chain, and has a reduced portion 34, which projects partially within the path of the slots 25, connecting the recesses 24 formed in the hub 22. The guide 32 is retained in its vertical position by means of oppositely disposed pairs of lugs 35, formed on the opposed walls of the housing 10 and the partition 28.

The cover plate 13, of the offset portion 12, of the housing, is formed with a concentrically disposed bearing sleeve 36, in which is supported a spindle 37 integrally formed with a cam plate 38, which, when properly mounted for operation, occupies the entire interior of the offset portion 12, and is disposed in a vertical plane and at right angles to the gear body 23.

The inner face of the cam plate 38 is formed with a single "radio-helical" cam element or member 39, which is adapted to continuously and progressively mesh with the radial curved teeth 40, formed on the periphery of the gear body 23. To effect the continuous and progressive meshing of the working surfaces of the cam-element 39 with the radial curved teeth 40, aforesaid, the said working surfaces of the former are disposed on a curve of approximate cycloidal formation, and are made angular in cross-section in one direction of the element for wardly from the inner starting point, or root of the curve, to a point approximately intermediate its length, and in a reverse angular or inclined relation for the remainder of its length to its outer end. This angularity of the cam-element 39, inclining first in one direction and then in a direction opposite thereto, causes the member 39 to support the entire weight or load, through the medium of the radial teeth 40, of the gear 23, at any given point in the travel of the lifting chain 26, and dispenses with any and all of the usual clutch or stop mechanisms heretofore provided for such purpose. The cam-member 39, as shown, is formed of a length to provide overlapping ends, so that two of the radial teeth 40, of the gear 23, are in constant engagement, and the space between the overlapped ends is of just sufficient greater width than that of a single

tooth to allow clearance of the same to and from engagement therewith, and in the revolution of the cam, the several teeth 36 are engaged consecutively.

To properly distinguish the approximate cycloidal curve formation of the cam-element 39, the same has been designated "radio-helical", since the motion defined by its travel is radially or trans-axially, and at right angles to the axis of the cam plate 38, and its direction of operation in the present instance is clockwise or right-handed.

The end of the spindle 37, of the cam-plate 38, is of a length to project outwardly of the bearing sleeve 36, and to support thereon a drive wheel or pulley 41, the latter being secured in position by means of a set nut 42, or in any other suitable or desired manner, and is preferably formed with a convexed body portion 43, which admits of the rim 44 rotating in the plane of the bearing sleeve 36. The rim 44 is formed with a series of recesses 45 having the shape and of a size to receive alternate links 47 of an operating chain, and slots 46 connecting the recesses 45 and of a shape and size 90 to receive the alternate links 48, of the chain 47.

Supported from the housing 10, by means of bracket arms 49, is a looped guide 50 which overlies and surrounds the upper portion of the pulley or wheel 41, in a manner to prevent the displacement of the chain during the strain thereon for the rotation of the drive wheel. To retain the guide 50 in a horizontal plane, the housing 10 is formed with stepped shoulders 51 and 52, the latter underlying the inner bar 53, of the looped portion of the guide for the purpose.

The inner end of the chain 26, is attached 105 to a screw 55, which is engaged in spaced lugs formed with the housing 10 and the removable side wall 11. By so fastening the chain it prevents the operator running the chain off the hub 22.

The invention contemplates the filling of the chamber 56, inclosed by the partition wall 28, the removable side wall 11, of the housing, and the cap plate 13, of the offset portion 12, with oil, whereby the moving 115 parts of the device operate with a minimum amount of friction.

Having thus described the desired embodiment of the invention, it is to be thoroughly understood that various changes 120 in the detailed construction and arrangement of the parts may be resorted to without departing from the spirit and scope of the same.

Having thus fully described the invention, what is claimed, is:—

In a hoisting mechanism, the combination with a housing, a disk mounted in the hous-

ing and having a single cam projecting from one face thereof, means for rotating said disk, a gear wheel mounted in the housing at right angles to said disk, one face 5 of said gear wheel being substantially in a plane with the axis of the disk, the teeth of the gear wheel being radial and engaging the cam, the opposite faces of said teeth be-

ing similar and the opposite corners of the opposite faces of the teeth being disposed 10 in alinement and parallel with a line drawn through the axis of the gear wheel, and a chain wheel rotatable with the gear wheel.

In testimony whereof I affix my signature.

HENRY J. SCHMICK.
